CLAIM

The ornamental design for a loader machine seat as shown and described.

DESCRIPTION

FIG. 1 is a front left perspective view of a loader machine seat showing our new design;

FIG. 2 is a top right perspective view thereof;

FIG. 3 is a front elevation view thereof; and,

FIG. 4 is a top plan view thereof.

In the drawings, the broken lines depict portions of the loader machine seat that form no part of the claimed design.
